US0D1004722S

(12) **United States Design Patent** (10) **Patent No.:** **US D1,004,722 S**
(45) **Date of Patent:** **** Nov. 14, 2023**

(54) **TUBING COMPONENT**

(71) Applicant: **P&P IMPORTS LLC**, Irvine, CA (US)

(72) Inventors: **Peter Engler**, Newport Beach, CA (US); **Peter Tanoury**, Newport Beach, CA (US)

(**) Term: **15 Years**

(21) Appl. No.: **29/836,739**

(22) Filed: **Apr. 28, 2022**

Related U.S. Application Data

(63) Continuation of application No. 29/682,980, filed on Mar. 8, 2019, now Pat. No. Des. 962,366.

(57) **CLAIM**

The ornamental design for a tubing component, as shown and described.

DESCRIPTION

FIG. 1 is a perspective view of a tubing component showing our new claimed design in accordance with a first embodiment;

FIG. 2 is a bottom plan view thereof;

FIG. 3 is a top plan view thereof;

FIG. 4 is a front elevational view thereof;

FIG. 5 is a back elevational view thereof;

FIG. 6 is a perspective view of the first embodiment in an environment of use;

FIG. 7 is a perspective view of the tubing component showing our new claimed design in accordance with a second embodiment;

FIG. 8 is a top plan view thereof;

FIG. 9 is a bottom plan view thereof;

FIG. 10 is a front elevational view thereof;

FIG. 11 is a back elevational view thereof; and,

FIG. 12 is a perspective view of the second embodiment in an environment of use.

Broken lines in FIGS. 1-5 and 7-11 illustrate portions of the tubing component that form no part of the claimed design. Broken lines in FIGS. 6 and 12 illustrate environmental structure that form no part of the claimed design.

1 Claim, 12 Drawing Sheets
